NAP-BLOWING ATTACHMENT FOR CLIPPING-MACHINES.

1,052,934.

Specification of Letters Patent.

Patented Feb. 11, 1913.

Application filed December 15, 1911. Serial No. 666,019.

To all whom it may concern:

Be it known that I, HARRY B. MALLORY, a citizen of the United States, residing at Danbury, county of Fairfield, State of Connecticut, have invented an Improvement in Nap-Blowing Attachments for Clipping-Machines, of which the following is a specification.

This invention has for its object to provide a nap blowing attachment adapted for clipping machines generally and especially adapted for use upon hat clipping machines, which by means of films or thin sheets of air under pressure will raise the nap and place it in the best possible position for clipping just at the instant it is subjected to the action of the clipping mechanism. I am thereby enabled to clip the nap to a uniform length throughout a hat body at a single operation and thus effect a great saving of time in the clipping of hat bodies, and produce better and more uniform results than it has been possible to produce with any machine or attachment heretofore known to the trade. With these and other objects in view I have devised the novel blowing attachment which I will now describe, referring to the accompanying drawing forming a part of this specification and using reference characters to indicate the several parts.

Figure 1 is a view partly in elevation and partly in section, on the line 1—1 in Fig. 2, looking in the direction of the arrows, illustrating the application of my novel attachment to a clipping machine; Fig. 2 a section on the line 2—2 in Fig. 1, looking in the direction of the arrows; Figs. 3 and 4 are detail sectional views illustrating variations in the details of construction of the primary air delivering means; and Fig. 5 is a detail sectional view on an enlarged scale, illustrating the secondary air delivering means.

10 denotes a frame which may have vertical swinging movement, 11 a clipping cylinder carried by a shaft 12, 13 a bed knife and 14 a work carrying table or shoe over which the hat body or other material to be clipped, indicated by 15, is passed, feeding mechanism being omitted as it forms no portion of the present invention.

The gist of the invention lies in projecting primary and secondary films or thin sheets

of air upon the nap, in proper relation to the clipping mechanism. In its original form on the hat body the nap is in a confused, tangled state. The effect of the primary film or thin sheet of air is to straighten out the nap and turn it in two directions leaving a line of cleavage where the film of air strikes it. As the hat body moves toward the clipping mechanism, the secondary film of air, which is projected backward under the clipping cylinder and parallel with the line of movement of the hat body, causes the nap to stand upright, in which condition it passes under the clipping cylinder. Both the primary and secondary air delivering or blowing means may consist of any suitable air receiver provided with a continuous slit or a line of fine openings through which the air issues under pressure in the form of a film or thin sheet. As a relatively heavy pressure is required for the primary air delivering means as well as adjustability of the volume of air delivered, I preferably provide an elongated air chamber 16 to which air is supplied in any suitable manner as by a pipe 17 provided with a valve 18. This chamber is closed at the bottom by means of a regulating plate 19 and an adjusting plate 20 having corresponding contiguous edges between which is a very narrow slit 21 through which the air issues under pressure in the form of a film or thin sheet extending the entire length of the chamber. The direction of movement of the hat body as seen in Fig. 1 is from right to left. Upon certain kinds of work it is desirable that the film or sheet of air should strike the nap in a backward direction, as in Fig. 1. Under other conditions it is desirable that the film or sheet of air should strike the nap in a forward direction, as in Fig. 3, and under still other conditions it is found preferable that the sheet or film of air should strike the nap vertically, that is at right angles to its plane of movement, as indicated in Fig. 4. These different results are secured by varying the plane of the contiguous edges of the regulating plate and the adjusting plate, as clearly shown in Figs. 1, 3 and 4. The regulating plate is fixed in place. The adjusting plate, however, is made bodily movable toward or from the regulating plate in order to increase or

diminish the width of the slit and consequently the volume of air in the film or sheet which is projected upon the nap. For this reason the holes 22 in the adjusting 5 plate through which the screws 23 pass are shown as enlarged. It should be understood that upon some kinds of work, instead of a chamber with a continuous slit a pipe similar to pipe 29 (presently to be described) 10 and provided with a line of fine openings, might be substituted and would accomplish approximately the same result.

In practice, air is supplied to the chamber or pipe in greater quantity than can escape 15 therefrom through the slit or holes under any conditions of use, so that a constant and relatively heavy pressure is always maintained. The chamber is shown as provided with longitudinal ribs 24 for strengthening 20 purposes, the central rib being shown as provided with a wide top in order to deflect air entering from the supply pipe. Holes 25 are provided in the lower ends of the ribs to permit free passage of air therethrough so 25 that air may reach all portions of the slit freely. In Fig. 2, I have shown blades 26 extending longitudinally of the chamber. The function of these blades, which may or 30 may not be used as found desirable, is to cause the film or sheet of air to issue from the slit obliquely in the direction in which it is turned. The blades may incline in either direction as when it is desired to project the film or sheet of air obliquely toward 35 the brim or toward the tip of a hat.

27 denotes a guard which rests upon a washer 28 and is secured in place by the screws 23 that retain the adjusting plate. The function of this guard is to prevent air 40 from slit 21 blowing into the face of the operator. The secondary air delivering means as shown comprises a delivery pipe 29 provided with a line of fine openings 30 to which air is supplied by a pipe 31. This 45 secondary air delivering means is placed in front of the clipping mechanism, in the present instance under the bed knife, and the direction of the film or sheet of air is backward under the clipping cylinder 50 parallel with the table or shoe and at right angles to the nap fibers, the effect being to raise the inclined nap erect and against the knives of the clipping cylinder. As the nap has already been thoroughly 55 straightened out by the action of the primary air delivering means, the function of the secondary air delivering means is supplemental thereto. It does not require as much air pressure but coacts with the primary air current to raise the nap into position 60 to be properly acted upon by the clipping mechanism.

Having thus described my invention I claim:

1. An attachment for clipping machines 65 comprising a chamber for air under pressure, said chamber being closed at the bottom by a regulating plate and an adjusting plate having corresponding contiguous faces whereby a slit is formed between said 70 plates through which the air passes in a thin film or sheet.

2. The combination with a clipping cylinder and a bed knife, of a receiver for air under pressure provided with a delivery 75 opening through which the air passes in a film or sheet and a secondary air delivering means lying under the bed knife and coacting with the first mentioned air delivering means.

80 3. The combination with clipping mechanism and a work-carrying table, of primary air delivering means whereby air is projected in a film or sheet downward upon a nap passing over the table before it reaches the 85 clipping mechanism and a secondary air delivering means lying in front of the table whereby air is projected against the nap as it is moving forward.

90 4. In a machine of the character described, the combination with clipping mechanism, of a chamber for air under pressure having a slit in its lower end, means for adjusting the width of said slit, for the purpose set forth, and a secondary air delivering means 95 lying in front of and parallel with the clipping mechanism.

100 5. In a machine of the character described, the combination with clipping mechanism, of a chamber for air under pressure having a slit for causing the air to issue therefrom in a film or sheet, and means for varying the angle at which the film or sheet of air shall issue substantially as described, 105 for the purpose specified.

110 6. An attachment for clipping machines comprising a chamber for air under pressure, said chamber being provided with a slit through which the air issues in a film or sheet and with means for regulating the width of said slit.

115 7. In a machine of the character described, the combination with clipping mechanism, of means located in front of the clipping mechanism for delivering air in a film or sheet backward under the clipping mechanism.

In testimony whereof I affix my signature in presence of two witnesses.

HARRY B. MALLORY.
